M. C. NEWTON ET AL

COMBINED MOP AND WRINGER

Filed Jan. 5, 1927

UNITED STATES PATENT OFFICE.

MILO C. NEWTON AND JOSEPH A. GREMLING, OF DELPHOS, OHIO, ASSIGNEES TO THE
E. & N. MANUFACTURING COMPANY, OF DELPHOS, OHIO, A CORPORATION OF OHIO.

COMBINED MOP AND WRINGER.

Application filed January 5, 1927. Serial No. 159,074.

This invention relates to improvements in combined mops and wringers such as are used for scrubbing, wiping and cleansing floors or other surfaces in which a wringing device is employed in connection with the mop for twisting the mop cloth so as to expel the water therefrom without soiling the hands of the user.

The present invention has for an object 10 to provide a combined mop and wringer in which the mop cloth supporting and pressure applying member is so formed and so connected to the handle and cloth as to engage the mop substantially throughout the 15 portion thereof in engagement with the floor and hold the same flat against the floor and against lateral movement with respect to the pressure applying member.

A further object of the invention is to 20 provide a pressure applying and mop cloth supporting member which is so formed as to permit the cloth to be twisted throughout its length without interference with portions of the supporting member so that the forward end of the cloth can be wrung dry.

With the above and other objects in view, the invention may be said to comprise the device as illustrated in the accompanying drawings hereinafter described and particularly set forth in the appended claims, together with such variations and modifications thereof as will be apparent to one skilled in the art to which the invention appertains.

Reference should be had to the accompanying drawings forming a part of this specification, in which:

Fig. 1 is a perspective view of the mop showing the same in mopping position;

Fig. 2 is a side elevation showing the mop in wringing position and the mop cloth twisted; and

Fig. 3 is a section on the line indicated at 3-3 in Fig. 2, looking in the direction indicated by the arrows.

Referring to the accompanying drawings, the mop handle is indicated by the numeral 1 and has attached to its forward end a suitable ferrule 2 formed of sheet metal and provided with parallel downwardly extending ears 3 at the end of the handle. A relatively short link 4 is pivotally connected at its upper end between the ears 3 by means of a pivot 5 and at its lower end is pivotally connected to an elongated pressure applying

member 6 which is in the form of a flat sheet metal plate with parallel flanges 7 struck up from the body thereof adjacent the rear end to receive the link 4 between them, the link being connected to the flanges 60 7 by means of a pivot pin 8. The longitudinal side edges of the plate 6 are rolled back upon themselves to provide hollow edge beads 9 extending the full length of the plate. A mop cloth holder formed of wire is 65 rigidly secured to the forward end of the plate 6 and this holder comprises a substantially straight cross-bar 10, arched side portions 11 bent rearwardly and inwardly from the ends of the cross-bar and attaching end 70 portions 12 extending substantially at right angles to the bar 10 and adapted to fit within the hollow beads 9 of the plate. Suitable means is provided for limiting the movement of the end portions 12 of the holder 75 into the beads 9 such as indentations 13 in the bead with which the ends of the portions 12 engage.

On the handle 1 adjacent the rear end of the ferrule 2 there is mounted a holder for 80 the rear end portion of the mop cloth and this holder which is formed of a single piece of wire consists of a mop cloth receiving loop 14 formed by bending one end portion of the wire from which there extends a bearing portion 15 which extends through a central opening in the handle 1 in which there is mounted a bearing sleeve 16, the wire being bent above the handle at right angles to the bearing portion 15 to form a handle 17 85 90 by which the loop 14 may be turned to twist a mop cloth 18 supported on the loop 14 and cross-bar 10. The mop holding member at the forward end of the pressure applying plate 6 may be detached from the plate and 95 inserted through the loop of the mop cloth then into the beads 9 of the plate to secure the cloth on the cross-bar 10, and the end of the wire forming the loop 14 of the holder for the rear end of the mop is spaced from 100 the central bearing portion 15 to provide a gap 19 in the top of the loop through which the mop cloth may be inserted or removed.

The forward end of the plate 6 is cut away to provide a recess 20 at the rear of the cross-bar 10 and the rear end of the plate has cut away portions adjacent the side beads 9 forming recesses 21 at the rear end of the plate. The portion of the rear edge of the plate between the recesses 21 are 110

rolled over to provide a bead 22 which engages with the under-side of the ferrule 2 to limit the downward and rearward movement of the forward end of the plate 6 and to rigidly hold the plate in wringing position as shown in Fig. 2 of the drawing.

As shown in Fig. 1 of the drawing, the link 4 is adapted to swing forwardly about the pivot 8 to bring the forward end of the handle 1 into direct bearing engagement with the plate at substantially the center thereof so that when pressure is applied to the handle the plate is applied to the mop cloth resting on the floor with substantially uniform pressure throughout the length thereof so that the cloth will be held flat against the floor and be prevented from rolling up or sliding laterally beneath the plate. Furthermore, in this position of the mop, the cloth, which is stretched between the loop 14 and cross-bar 10, extends into the recesses 20 and 21 at the front and rear ends of the plate so that the cloth is securely held against lateral movement beneath the plate. When the mop is lifted from the floor, the plate 6 automatically swings to the position shown in Fig. 2, and the mop cloth can be twisted to wring out the water by simply turning the handle 17. This twisting of the mop cloth causes the same to assume a substantially cylindrical form and in order to wring the cloth dry from end to end it is necessary that the cloth be free to twist to substantially cylindrical form from the rear supporting loop to the bar supporting the forward end of the cloth, and to permit this twisting of the cloth the forward end of the plate is cut away to provide the recess 20 so that there is a clearance space between the cross-bar 10 and the plate sufficient to permit the cloth to be twisted tightly without being brought into binding engagement with the plate.

Having thus described our invention, what we claim is:

1. A wringer mop comprising a handle, means for supporting the rear end of a mop cloth comprising a wringer member rotatably mounted on the handle rearwardly of the forward end of the handle, means for supporting the front end of the cloth and for pressing the same against the floor in mopping, comprising a substantially flat elongated sheet metal plate having its longitudinal edges bent to form hollow beads, a cloth holding bar formed of wire and having a transverse cloth receiving portion and end portions adapted to fit within the hollow beads of said plate, and a pivotal connection between the forward end of the handle and said plate, the rear edge of the plate being engageable with the handle to limit the downward and rearward movement of the forward end of the plate and rigidly hold the plate during the wringing operation, the

forward edge of said plate being cut away between the beads to provide a recess of sufficient depth at the rear of said bar to accommodate the cloth when twisted to cylindrical form so as to permit the cloth to twist to the forward end thereof without binding against said plate.

2. A wringer mop comprising a handle, means for supporting the rear end of a mop cloth comprising a wringer member rotatably mounted on the handle rearwardly of the forward end of the handle, means for supporting the front end of the cloth and for pressing the same against the floor in mopping, comprising a substantially flat elongated sheet metal plate having its longitudinal edges bent to form hollow beads, a cloth holding bar formed of wire and having a transverse cloth receiving portion and end portions adapted to fit within the hollow beads of said plate, and a link pivoted at its upper end to the forward end of the handle and at its lower end to said plate between the center and rear end thereof, the rear edge of the plate having a central beaded portion adapted to engage the handle to limit the downward and rearward movement of the forward end of the plate and rigidly hold the plate during the wringing operation, said rear edge having recesses between the beaded portion and side edges of the plate to receive portions of the cloth and prevent the cloth from slipping laterally during the mopping operation.

3. A wringer mop comprising a handle, and mop cloth supporting means comprising a wringer member for supporting the rear end of the cloth which is rotatably mounted on the handle rearwardly of the forward end thereof and a substantially flat elongated pressure applying member pivotally connected to the forward portion of the handle, the rear end of the pressure applying member being engageable with the handle to limit the downward and rearward movement thereof, said pressure applying member having a cross bar rigidly secured thereto and extending across the forward end in advance of the body portion thereof to receive the forward end of the cloth, said body portion having a centrally disposed recess at its forward end rearwardly of said cross bar of a depth and width sufficient to accommodate the mop cloth when twisted to substantially cylindrical form, so as to permit the cloth to twist to the forward end thereof without binding against said body portion.

4. A wringer mop comprising a handle, a mop cloth, a rotatable wringer member carried by the handle rearwardly of its forward end, a substantially flat elongated cloth holding and pressure applying member overlying the mop cloth and pivotally connected intermediate its ends to the forward end of

the handle, said pressure applying member having a cross bar at its forward end over which the mop cloth is looped and being movable from a mopping position in which 5 it bears upon the mop cloth to a wringing position in which the mop cloth extends at an angle thereto from the cross bar to the wringer member, said pressure applying member and cross-bar being spaced to form 10 an opening between the body portion thereof and the cross bar of a width and depth to provide clearance for the mop cloth, when

the pressure applying member is in wringing position, sufficient to accommodate the mop cloth when twisted to substantially cylindrical form and to permit the cloth to twist freely between the wringer member and cross bar without binding against the body portion of the pressure applying member. 15

20 In testimony whereof, we hereunto affix our signatures.

MILO C. NEWTON.

JOSEPH A. GREMLING.
